BLENDER

William G. Barnard, Jr., and W. Grover Barnard, Olmsted Falls, Ohio, assignors to Vita Mix Corporation

Filed Jan. 11, 1971, Ser. No. 105,777

Term of patent 14 years

Int. Cl. D7—04

U.S. Cl. D89—1 B

The figure is a top perspective view of a blender showing the front and right side of our new design.

The left side is substantially similar to the side shown, the handle being omitted therefrom, and the back is a mirror image of the front except that the control panel and knob are omitted therefrom.

We claim:

The ornamental design for a blender, as shown and described.
